UNITED STATES PATENT OFFICE.

JOSEPH G. HESTER, OF WASHINGTON, DISTRICT OF COLUMBIA, ASSIGNOR
TO JULIUS LANSBURGH, OF SAME PLACE.

WRITING-PEN AND HOLDER.

SPECIFICATION forming part of Letters Patent No. 278,239, dated May 22, 1883.

Application filed October 7, 1881. (No model.)

To all whom it may concern:

Be it known that I, JOSEPH GOODMAN HESTER, a citizen of the United States, residing at Washington, in the District of Columbia, have invented certain new and useful Improvements in Pens and Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a novel and useful writing-pen, in combination with a holder having a central longitudinal bore adapted to receive a reciprocating ejector of limited stroke, the said ejector serving to liberate the pen from its seat, and so constructed as to admit the holder being made of small diameter; and my improvement consists in the novelty of the construction of the several parts, as hereinafter set forth, and specifically pointed out in the claims.

The object of the invention is to provide a cheap, serviceable, efficient, and durable pen, which may readily be ejected from its seat within the holder without soiling the fingers of the writer. The construction and form of the pen-shank is such that it holds itself securely in place within either end of a tubular holder by inherent spring and frictional contact without the aid of additional clamping or gripping mechanism, said pen being cut or struck up by dies, and the shank being turned over to form a tapering barrel provided with an abrupt abutting head, which abutting head in practice is turned over flat against the upper peripheral surface of the pen-shank. The further object of my invention is to provide a tubular case, the bore of which is somewhat smaller in diameter than the barrel-shank of the pen it is adapted to receive, so that after said pen is inserted in place the wings of the shank will dis-tend and snugly rest against the inner surface of the tubular case. The tubular case is provided within its bore with a longitudinally-reciprocating piston or plunger, which serves as a means for ejecting the pen. Said ejecting-plunger is cut away at or near its middle, forming

ing a longitudinal groove or recess, into which takes an operating pin or lug located upon the holder, and having its point extending a required distance within the inner surface of said holder, said pin or lug limiting the stroke of the ejector and preventing its displacement. The relative location of the recess upon the ejecting-plunger and the position of the pin or lug upon the holder are such that they will admit the ejector to extend outwardly from either end of the tubular holder a distance approximating to the length of the pen-shank, as hereinafter set forth. The longitudinally-reciprocating plunger or ejector is covered by Letters Patent No. 246,769, granted to me, dated September 6, 1881, and is not herein broadly claimed. The tubular holder is preferably made of layers of paper or fibrous substance or plastic pulp, the mass being connected by adhesive material and formed upon a mandrel, as fully described and claimed in another application for Letters Patent which I have filed.

Referring to the accompanying drawings, in which similar letters of reference indicate like parts on each figure, Figure 1 is a detail perspective view of the pen constructed according to my invention. Fig. 2 is a longitudinally-central sectional view of a pen-holder embodying my invention, parts being in elevation. Fig. 3 is a detail perspective view of the ejecting plunger or piston. Fig. 4 is a perspective view of the pen-blank before being folded over.

A represents the holder, which may have any inner and outer configuration, having a longitudinal bore, *a*, in which is introduced an ejecting-plunger, *B*, provided with a recess or groove, *b*, at one side thereof, at or near its middle. This groove *b* receives a pin or lug, *c*, which is inserted in the holder *A*, and extends a required distance within the bore *a*.

C is the pen, having an angular cut-away portion, *d*, to form spring-wings *e*, and having an upper extension or head-piece, *f*, as shown, all formed of a single piece of metal.

The mode of construction and adaptation is as follows: The tubular case *A* is prepared, having any suitable form of exterior, the ejector *B*, with its properly-recessed portion, *b*, is then passed within the bore *a* and the limiting pin or lug *c* properly placed in position, and

the holder is complete. The ejector being longer than the holder, one end necessarily protrudes and the opposite end is flush with the receiving end of the holder before the insertion of the pen, which flush end is ready for reception of the pen, which is easily placed in position, and can be ejected therefrom by longitudinal pressure upon the plunger B. The blank for the pen is cut by dies, the shank being provided with an extension or abutting head, f, and having wings e, to be folded over and constitute a tapering tubular barrel-shank, its apex or smaller diametrical portion being toward the head. It will thus be plainly understood that the wings, which have been sprung over to make the barrel-shank, will have a tendency, if subjected to lateral pressure, as will be the case when inserted within the holder A, to distend again. Thus as soon as the pen is inserted within the holder said wings will press against the inner surface thereof and rest firmly in position by frictional contact.

I have confined my description to a pen-shank tubular in form, but desire to be understood that it need not be necessarily circular. Its sides may be flattened or rectangular, and be within the scope of my invention, the condition being essential that the wings comprising said shank shall be so turned or bent over that when compressed and inserted within the handle they will have a tendency to spring back or open against the inner surface of the holding tubular case, the opening or bore of which holder may also be of any configuration that taste or convenience may dictate to correspond with the shape of the shank of the pen.

It will be readily understood that the pen

may be inserted in either end of the holder, and this is an important feature of my invention for obvious purposes.

Having now fully described my invention, what I claim is—

1. A writing-pen having spring-wings folded or bent to form a shank, and an abutting head adapted to serve with a holder having a 45° central longitudinal aperture, and with an ejector, as and for the purposes set forth.
2. The holder A, having central longitudinal bore, a, combined with an ejector, and with a pen having a spring-shank and an abutting 50° head against which the plunger abuts to liberate and eject the pen, as specified.
3. The holder A, having axial bore a and pin e, and supplied with a longitudinally-reciprocating ejector, B, having recess b, constructed as set forth, adapted to receive a pen at either end, substantially as described.
4. The combination of a pen and its holder, open at both ends, composed of the following elements: a hollow sheath or holder, A, supplied with a longitudinally-reciprocating ejector, B, provided with a side recess, b, a pin, e, extending within said case, a pen, C, having cut-away portions d, wings e, and head-extension f, all constructed and arranged as set forth, as and for the purpose stated, substantially as described.

In testimony whereof I affix my signature in presence of two witnesses.

JOSEPH GOODMAN HESTER.
